UNITED STATES PATENT OFFICE

112,335

DESIGN FOR A TEXTILE FABRIC OR SIMILAR ARTICLE

John W. H. Brooks, Wynnewood, Pa.

Application October 25, 1938, Serial No. 80,671

Term of patent 3½ years

To all whom it may concern:

Be it known that I, John W. H. Brooks, a citizen of the United States, residing in the city of Wynnewood, County of Montgomery, and State of Pennsylvania, have invented a new, original, and ornamental Design for a Textile Fabric or Similar Article, of which the following is a specification, reference being had to the accompanying drawing, forming a part thereof.

The drawing is a plan view of a textile fabric or similar article showing my new design.

I claim:

The ornamental design for a textile fabric or similar article, as shown.

JOHN W. H. BROOKS.
